UNITED STATES PATENT OFFICE.

ELBERT H. BEERS, OF PHILADELPHIA, PENNSYLVANIA, ASSIGNOR OF ONE-HALF TO
CHARLES S. WEIERMAN, OF PHILADELPHIA, PENNSYLVANIA.

STOCKING.

1,116,214.

Specification of Letters Patent.

Patented Nov. 3, 1914.

Application filed October 25, 1913. Serial No. 797,269.

To all whom it may concern:

Be it known that I, ELBERT H. BEERS, a citizen of the United States, residing at Philadelphia, in the county of Philadelphia and State of Pennsylvania, have invented new and useful Improvements in Stockings, of which the following is a specification.

This invention relates to stockings, and has for its primary object the provision of means whereby the same may be adjusted to the wearer expeditiously and supported in place without necessitating the provision of a leg-embracing garter or the like.

Another object of the invention is the provision of a stocking constructed of relatively elastic fabric slit at a suitable point so as to provide separable sides that are adapted to be adjusted to overlap one another to hold the upper portion of the stocking completely closed around the leg.

Another object of the invention is the provision of a stocking slit vertically in a portion of its length and preferably near its upper end and at one side only and provided respectively at the sides of the slit portion with mating fastening devices engageable with one another to hold the slit portion properly closed and the stocking adjusted to embrace the leg as necessary to a proper suspension of the stocking.

A still further object of the invention is the provision of a stocking capable of adjustment around the leg and provided with means for holding the stocking operatively adjusted, and further the provision of a foldable cuff formed at the upper end of the stocking and adapted to be folded so as to entirely conceal the adjustable portion thereof and the holding means.

In the accompanying drawings:—Figure 1 is a side view of a portion of a stocking constructed in accordance with my invention and illustrating the cuff in an extended position; Fig. 2 is a similar view, showing the cuff folded to conceal the fastenings; Fig. 3 is a vertical section through the upper portion of the stocking, showing the cuff folded over the fastenings.

The stocking 1 shown in the drawing is preferably formed of relatively elastic material such as silk or the like reinforced at its upper end by folding the material on itself in the usual manner. The stocking

is slit vertically in its main length, as at 2, so as to provide relatively adjustable portions 3 and 4 that are adapted to be adjusted to overlap each other. The portion 4 is provided between its ends with a resilient head 5, while the portion 3 is provided with a plurality of resilient sockets 6 arranged in the same general line and adapted for interchangeable connection with the mating fastening 5 as may depend upon the adjustment of the stocking to be obtained around the leg. From this construction, and incident to the fact that the stocking is constructed of material having such inherent elastic qualities as to permit the same to be respectively contracted and expanded, it obviously appears that after the mating fastenings 5 and 6 are connected with each other the stocking will be brought under sufficient circumferential tension to permit the same to be supported from the leg without necessitating the provision of the usual garter or like means of suspension.

It is described that the split 2 is formed in the stocking below the upper end thereof. This is desirable in order that the portion 7 at the extreme upper end of the stocking 89 may serve the purpose of a foldable cuff which may be folded over and against the adjacent body of the stocking in a manner to entirely conceal the fastenings 5 and 6, as will be understood.

As shown in the drawings the slit mentioned in the previous embodiment of the invention is formed on the side of the stocking. I wish to be understood, however, that this is not entirely essential and that the slit 90 may be formed on the line of seam at the back of the stocking, as shown at 8 in Fig. 5 of the drawing.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as claimed.

I claim:—

A stocking formed of elastic material and having a vertical slit in the upper portion

of the leg located entirely at a point spaced from the top edge, means on opposite sides of the slit to secure said sides together and close the slit and a foldable cuff on the 5 stocking leg, above the slit and adapted to be folded over the slit to conceal the same and to also conceal the fastening devices.

In testimony whereof I affix my signature in presence of two witnesses.

ELBERT H. BEERS.
